UNITED STATES PATENT OFFICE

2,228,928

REFRIGERATING APPARATUS

Donald H. Reeves, Dayton, Ohio, assignor to General Motors Corporation, Dayton, Ohio, a corporation of Delaware

Application August 19, 1937, Serial No. 159,936

11 Claims. (Cl. 62—108.5)

My invention relates to refrigeration and particularly to freezing devices employed in household refrigerators.

An object of my invention is to provide an improved metallic freezing unit for refrigerators whereby ice blocks can be readily removed therefrom without applying artificial heat thereto.

Another object of my invention is to provide an ice tray unit with a single manually actuated means which when operated will separate the unit from its freezing support in or on a cooling element of a refrigerating system, will elevate a removable grid structure disposed in the tray together with ice blocks adhering thereto relative to the tray and will also break ice blocks loose from the grid structure to thereby facilitate the harvesting of ice blocks from the unit.

Another object of my invention is to provide a freezing unit comprising a tray and a grid structure removably positioned in the tray with a handle movable in a single direction of motion for removing the unit from its freezing support and elevating the grid structure relative to the tray and for also releasing ice blocks from the grid structure.

In carrying out the foregoing objects, it is a still further and more specific object of my invention to provide an improved freezing unit comprising a tray and a grid structure removably positioned in the tray, which grid structure includes a plurality of ice compartment forming walls that are movable relative to one another and one of which walls extends over an edge of the tray with a single means preferably movable in a single direction of motion for successively removing the unit from its support, for elevating the grid relative to the tray and for moving certain walls of the grid structure relative to other walls thereof to release ice blocks from the ice compartments.

Further objects and advantages of the present invention will be apparent from the following description, reference being had to the accompanying drawings, wherein a preferred form of the present invention is clearly shown.

In the drawings:

Fig. 1 is a top plan view of a freezing unit constructed in accordance with my invention;

Fig. 2 is a side view of the unit disclosed in Fig. 1 and taken on the line 2—2 thereof showing the unit in a normal supported position on a freezing support of an evaporator of a refrigerating system;

Fig. 3 is a view similar to Fig. 2 showing the

unit and ice frozen therein elevated relative to its freezing support;

Fig. 4 is a view similar to Figs. 2 and 3 showing the grid structure and ice adhering thereto elevated relative to the tray of the unit;

5

Fig. 5 is a front end view of the freezing unit;

Fig. 6 is a view disclosing certain walls of the grid structure disposed within the tray of the unit moved relative to other walls thereof for releasing ice blocks therefrom;

10

Fig. 7 is a sectional view taken on the line 7—7 of Fig. 2 showing the locking arrangement of the movable portions of the longitudinal grid wall with the rear end transverse grid wall; and

15

Fig. 8 is a sectional view taken on the line 8—8 of Fig. 2 showing the arrangement of locking other walls of the grid together.

Referring to the drawings, for the purpose of illustrating my invention, I have disclosed therein a metal ice tray 10 having side walls 11, a bottom wall 12 and opposed end walls 13 and 14. The tray side walls 11 and the rear wall 14 thereof converge outwardly toward the top of the tray. The tray front wall 13 is converged outwardly toward the top of the tray a greater distance 25 than other walls thereof for a purpose which will become apparent hereinafter. The walls 11, 13 and 14 of tray 10 have their upper portion rolled over, as at 15, to provide a rim around the top of the tray to stiffen same. A portion of the 30 metal of tray 10 at the front thereof is extended downwardly from rim 15, as at 16, to provide a mounting for a heavy metal piece 17 secured thereto by screws 18. The metal piece 17 has a pair of rounded ears or bearings 19 formed 35 thereon which receive holes provided in the legs 21 of a handle member, generally represented by the reference character 22, to pivotally secure the handle member 22 to the tray 10. This handle member 22 has a three-fold purpose and therefore forms a single means for carrying out three functions in accordance with the objects of the present invention. In addition to the handle portion 23 of handle member 22, this member includes a cam surface 24 formed along the lower 40 edge of its legs 21. Member 22 also includes an integral cross part 25 which is normally disposed between the handle portion 23 thereof and the front of tray 10. The handle portion 23 of handle member 22 has a finger 26 depending therefrom 45 at the center thereof. The various portions of the handle member 22 and their construction and arrangement will become apparent in the course of the description of the operation of the device disclosed.

40

45

50

55

A unitary metallic grid structure, generally represented by the reference character 30, is removably disposed within tray 10 and divides the interior of the tray into a plurality of rows 5 of open-top molds, cells or compartments 31. This grid structure may be of any suitable construction but is preferably constructed somewhat in accordance with the structure disclosed in my copending application, Serial No. 129,443, filed March 6, 1937, now matured into Patent No. 2,196,476. The grid 30 comprises a longitudinal wall constructed of two rigid metal parts 32 and 33 disposed one above the other in substantially the same vertical plane. These parts 15 32 and 33 of the longitudinal wall are movable relative to one another and are locked between a plurality of spaced apart transverse walls 34. The manner of assembling the walls of grid 30 to one another and of locking same together to 20 form a unitary structure is fully described in my copending application above referred to and for this reason will not be herein described in detail. It will be noted that the parts 32 and 33 of the longitudinal grid wall are movable relative to one another and that by moving these parts the transverse walls 34 are moved or tilted, relative to the longitudinal wall. It is also to be noted that the transverse grid walls 34 are normally disposed at an acute angle relative to 25 a line extended perpendicular to the longitudinal extension of the grid structure and thereby provide the ice block compartments 31 with a parallelogram form. Movement of the transverse walls 34 out of their acute normal angled disposition into a substantially vertical position breaks the ice blocks loose from the grid structure and enlarges the compartments 31 as fully described in my copending application above referred to.

40 In the present disclosure, a portion of the upper part 32 of the two-part longitudinal grid wall, adjacent the sliding front end connection 35 of the two parts 32 and 33, is extended over the top edge or rim 15 of tray 10 at the front end 45 of the tray, as at 36, and is then directed downwardly, as at 37, to form a finger. The downwardly directed finger portion 37 of the grid structure is normally disposed between the cross part 25 and finger 26 of the handle member 22. 50 A part of the lower edge of the extended portion 36 of grid wall 32 is shaped to provide a camming surface 38 adapted to cooperate with and be engaged by the cross part 25 on the handle member 22 for a purpose to be presently described.

55 The parts of the unit in the present invention are, during freezing of water thereon, normally disposed in the position illustrated in Fig. 2 of the drawings wherein I have disclosed a support 39 which represents a freezing shelf or the like of a cooling element or unit of a refrigerating system such as is usually provided in a cooling element or unit of a household refrigerating apparatus.

Assume that water has been frozen in tray 60 10 of the freezing unit in the form of blocks 40 in compartments 31 by the cooling effect produced by the freezing support 39 of a cooling element, and it is now desirable to remove the unit from its support and to remove the ice blocks from the unit. The handle portion 23 of handle member 22 is grasped by the hand and moved downwardly and outwardly away from tray 10 about its pivotal mountings 19. This initial movement 70 of handle member 22 causes the cams 24 to exert a force against the unit's support 39 to thereby 75 elevate the freezing unit, including tray 10, grid 30 and ice blocks 40 contained therein, relative to its support on the cooling unit or element. This initial movement of handle member 22, to elevate the freezing unit relative to its support 39, causes the cross part 25 of the handle member to move toward the cam surface 38 provided on the finger portion of the upper grid wall part 32 of grid structure 30 as is illustrated in Fig. 3 of the drawings. The ice bond between the freezing unit and its support 39 having now been broken, further movement of the handle member 22 about its pivotal mountings 19 in the same direction of motion will cause the cross part 25 thereof to slide against the cam surface 38 formed on the finger portion of the grid wall part 32. The sliding engagement of cross part 25 of handle member 22 with the camming surface 38 applies force to the grid structure 30 and elevates same together with ice blocks 40 adhering thereto relative to the tray 10 of the unit. This further movement of handle member 22 to elevate the grid and ice blocks relative to the tray is illustrated in Fig. 4 of the drawings and it will be noted that this force applied to the grid structure 30 has not as yet caused movement of the movable grid walls relative to one another therefore necessitating an additional movement of the handle member 22 in its same direction of motion to move the grid walls and 30 release ice blocks from compartments 31. Therefore, an additional downward movement of the handle member 22 about its pivotal mountings 19 causes the cross part 25 thereof to apply force, in a direction outwardly of the front end 35 of tray 10, upon the finger portion 37 of the grid wall part 32. This outward force applied to the upper longitudinal grid wall part 32, while the lower longitudinal grid wall part 33 is abutting the front end wall 13 of tray 10, moves the wall 40 part 32 lengthwise of the wall part 33. The lengthwise sliding movement of the longitudinal wall upper part 32 relative to the longitudinal wall lower part 33 causes movement or tilting of the transverse walls 34 of grid 30, within the 45 slots provided in the two parts of the longitudinal wall, out of their normal acute angled disposition into substantially a vertical position to break the ice cubes 40 loose from the grid structure and to enlarge the ice compartments 31 and permit 50 the ice blocks to fall out of same as is illustrated in Fig. 6 of the drawings. This movement or tilting of the transverse walls 34 of grid structure 30 is preferably progressive from one end to the other end of tray 10 to facilitate the breaking 55 of ice blocks from the grid as fully described in my copending application hereinbefore referred to. The grid 30 may then be removed from tray 10 to facilitate removal of the ice blocks from the tray. When the grid 30 is replaced in tray 10 the finger portion 37 thereof is again positioned between the cross part 25 and handle portion 23 of the handle member 22, and the finger 26 formed on member 22 engages the grid finger 37 to position the grid in its normal position with the transverse walls 34 thereof disposed at an acute angle to form the parallelogram-shaped ice block compartments 31. The engagement of cams 24 on handle member 22 with the support 39, as shown in Fig. 2 of the 70 drawings, holds the finger 26 against finger 37 to thereby maintain the grid structure 30 in its normal freezing position.

While I have described one form of grid structure disposed in the tray of my improved 75

freezing unit, it is to be understood that other forms of grid structures may be used without departing from the spirit of the present invention. For example, a means for moving certain walls of a grid structure relative to other walls thereof, which is not essentially a part of the ice block compartment walls such as I have disclosed in my copending application Serial No. 98,213, filed August 27, 1936, may be employed.

1 In this latter case the bar member extending longitudinally over the grid structure would be projected over the front edge of the tray and would be operatively associated with a handle member substantially of the type herein disclosed. It is also to be understood that, while I have disclosed a certain form of handle member operable in a single direction of motion for performing three different functions, other forms coming within the realm of my invention 5 may be employed. The tray and grid structure disclosed is preferably treated or coated with a water repellent material to reduce the bond between ice blocks and the tray and grid structure to thereby facilitate operations of the handle as 10 described.

From the foregoing it will be seen that I have provided an improved freezing unit for use in household refrigerators and that the unit comprises a single means operable in a single 15 direction of motion for breaking an ice bond between the unit and its support on a cooling element, for elevating the grid structure together with ice blocks adhering thereto relative to the tray of the unit and for also breaking 20 ice blocks loose from the grid structure to permit harvesting of the blocks from the unit. The provision of a single means for carrying out the three ice bond breaking operations described and illustrated with a minimum of force greatly 25 simplifies the harvesting of ice blocks from a refrigerator and overcomes objections to prior devices wherein utmost effort is required in operating several different mechanisms to carry out the operations performed by the single means 30 in the present invention. My improved freezing unit is constructed entirely of metal to thereby retain the fast freezing characteristics of metal 35 grid and tray combinations.

While the form of embodiment of the invention as herein disclosed, constitutes a preferred form, it is to be understood that other forms might be adopted, all coming within the scope 40 of the claims which follow.

What is claimed is as follows:

55 1. A freezing unit adapted to be placed in or on a freezing support of a cooling element of a refrigerating system comprising in combination, a tray, a grid structure removably disposed in said tray, said grid structure including a plurality of walls dividing the interior of said tray into a plurality of ice block compartments, certain of said grid walls being movable relative to other walls thereof, and a single means associated with said unit and movable relative thereto for elevating the unit relative to its support and for elevating said grid structure together with ice blocks adhering thereto relative to said tray and for also moving said certain grid walls relative to said other walls thereof to release ice blocks from the grid structure.

70 2. A freezing unit adapted to be placed in or on a freezing support of a cooling element of a refrigerating system comprising in combination, a tray, a grid structure removably disposed in said tray, said grid structure including a plural-

ity of walls dividing the interior of said tray into a plurality of ice block compartments, certain of said grid walls being movable relative to other walls thereof, and means associated with said unit and movable relative thereto in a single 5 direction of motion for elevating the unit relative to its support and for elevating said grid structure together with ice blocks adhering thereto relative to said tray and for also moving said certain grid walls relative to said other 10 walls thereof to release ice blocks from the grid structure.

3. A freezing unit adapted to be placed in or on a freezing support of a cooling element of a refrigerating system comprising in combination, a tray, a grid structure removably disposed in said tray, said grid structure including a plurality of walls dividing the interior of said tray into a plurality of ice block compartments, certain of said grid walls being movable relative to other walls thereof, a handle carried by said tray and movable relative thereto, said handle having a portion thereof adapted to engage said unit support and elevate the unit relative to its support, said handle having another portion 25 adapted to engage a portion of said grid structure and elevate the grid together with ice blocks adhering thereto relative to said tray, and said another portion of said handle being adapted to move said certain walls of said grid structure 30 relative to other walls thereof to release ice blocks therefrom.

4. A freezing unit adapted to be placed in or on a freezing support of a cooling element of a refrigerating system comprising in combination, a tray, a grid structure removably disposed in said tray, said grid structure including a plurality of walls dividing the interior of said tray into a plurality of ice block compartments, certain of said grid walls being movable relative to other walls thereof, a handle pivotally mounted upon said tray and movable in a single direction of motion about its pivot relative to said tray, said handle having a cam formed thereon adapted upon initial movement of the handle in said 35 single direction of motion to engage said unit support and elevate the unit relative to its support, said handle having a portion formed integral therewith in spaced relation to said cam adapted upon further movement of the handle 45 in said single direction of motion to engage a portion of said grid structure and elevate the grid together with ice blocks adhering thereto relative to said tray, and said last named portion of said handle being adapted upon still further movement of the handle in said single direction of motion to move said certain walls of said grid structure relative to other walls thereof to release ice blocks therefrom.

5. A freezing unit adapted to be placed in or on a freezing support of a cooling element of a refrigerating system comprising in combination, a tray, a grid structure removably disposed in said tray, said grid structure including a two-part longitudinal wall and a plurality of transverse walls dividing the interior of said tray into a plurality of rows of ice block compartments, said parts of said two-part longitudinal wall being movable relative to one another and being constructed and arranged to cause movement of 60 said transverse walls, one part of said two-part longitudinal wall having a portion thereof projected over an edge of said tray and extending outwardly from said tray edge, and a single means adapted to elevate said unit relative to 65 said transverse walls, one part of said two-part longitudinal wall having a portion thereof projected over an edge of said tray and extending outwardly from said tray edge, and a single means adapted to elevate said unit relative to 70 said transverse walls, one part of said two-part longitudinal wall having a portion thereof projected over an edge of said tray and extending outwardly from said tray edge, and a single means adapted to elevate said unit relative to 75

- its support and having a portion thereof adapted to engage said projecting portion of said two-part longitudinal grid wall for elevating the grid structure together with ice blocks adhering thereto relative to said tray and for moving said one part of said two-part longitudinal grid wall relative to the other part thereof to move said transverse grid walls and release ice blocks from the grid structure.
10. 6. A freezing unit adapted to be placed in or on a freezing support of a cooling element of a refrigerating system comprising in combination, a tray, a grid structure removably disposed in said tray, said grid structure including a two-part longitudinal wall and a plurality of transverse walls dividing the interior of said tray into a plurality of rows of ice block compartments, said parts of said two-part longitudinal wall being movable relative to one another and being 15 constructed and arranged to cause movement of said transverse walls, one part of said two-part longitudinal wall having a portion thereof projected over an edge of said tray and extending outwardly from said tray edge, and manually 20 actuated means carried by said unit and movable in a single direction of motion for elevating said unit relative to its support and having a portion thereof adapted to engage said projecting portion of said two-part longitudinal grid wall for 25 elevating the grid structure together with ice blocks adhering thereto relative to said tray and for moving said one part of said two-part longitudinal grid wall relative to the other part thereof to move said transverse grid walls and release 30 ice blocks from the grid structure.
7. A freezing unit adapted to be placed in or on a freezing support of a cooling element of a refrigerating system comprising in combination, a tray, a grid structure removably disposed in 35 said tray to divide the interior thereof into a plurality of ice block compartments, and a single means associated with said unit and movable relative thereto for elevating the unit relative to its support and for elevating said grid structure together with ice blocks adhering thereto 40 relative to said tray and for also releasing ice blocks from the ice compartments of said grid structure after same has been elevated relative to the tray.
50. 8. A freezing unit adapted to be placed in or on a freezing support of a cooling element of a refrigerating system comprising in combination, a tray, a grid structure removably disposed in said tray to divide the interior thereof into a 55 plurality of ice block compartments, and man-
- ually actuated means carried by said tray and movable in a single direction of motion for elevating the unit relative to its support and for elevating said grid structure together with ice blocks adhering thereto relative to said tray and for also releasing ice blocks from the ice compartments of said grid structure after same has been elevated relative to the tray.
9. The combination, with a cooling unit of a refrigerating system, of a freezing unit removably supported on the cooling unit, said freezing unit including a tray and a grid structure disposed in the tray for dividing the interior thereof into a plurality of ice block compartments and being movable relative to the tray, said grid structure having a plurality of walls certain of which are movable relative to certain others thereof, and a single means movably mounted on one of said units for causing relative movement between said freezing unit and its support 10 on said cooling unit and for elevating said grid structure together with ice blocks adhering thereto relative to said tray and for also moving said movable grid walls relative to said other walls thereof after said grid structure has been elevated relative to the tray to release ice blocks from said ice compartments.
10. A freezing unit adapted to be removably supported on a cooling unit, said freezing unit comprising a tray and a unitary grid structure 15 removably disposed in the tray, said grid structure including a two-part longitudinal wall and a plurality of spaced apart walls interlocked therewith and extending transversely thereof for dividing the interior of said tray into a plurality of ice block forming compartments, said parts of said two-part longitudinal grid wall being movable relative to one another and being constructed and arranged to cause movement of said transverse grid walls, a single means movably mounted upon one of said units for causing relative movement between said freezing unit and its support on the cooling unit, and said single means having a portion thereof engageable with one part of said two-part longitudinal grid wall for 20 moving said parts relative to one another to cause said movement of said transverse grid walls for breaking the ice bond between ice blocks and said grid and tray.
11. A device constructed in accordance with 25 the terms of claim 10 wherein the transverse grid walls are normally inclined with respect to the vertical and are tilted in a direction toward the vertical to enlarge the ice block compartments.

DONALD H. REEVES. 55
